UNITED STATES PATENT OFFICE.

GEORGE H. EVANS, OF MEMPHIS, TENNESSEE.

RAIL-JOINT CHAIR.

1,125,501.

Specification of Letters Patent.

Patented Jan. 19, 1915.

Application filed March 16, 1914. Serial No. 825,116.

To all whom it may concern:

Be it known that I, GEORGE H. EVANS, a citizen of the United States, residing at Memphis, in the county of Shelby and State of Tennessee, have invented certain new and useful Improvements in Rail-Joint Chairs, of which the following is a specification, reference being had to the accompanying drawings.

10 This invention relates to new and useful improvements in rail joint chairs and more particularly to a joint chair, wherein the use of nuts, bolts and fastening means of a like character are eliminated, the main object of the invention being the provision 15 of a device of this character, wherein the meeting ends of two rails are securely held against lateral or longitudinal movement, without the use of bolts, nuts and fastening 20 means of a like character.

Another object of the present invention is the provision of a rail joint chair which will possess advantages in points of efficiency and durability, is inexpensive to 25 manufacture and, at the same time, simple in construction and operation.

With the above and other objects in view, the invention consists in the novel features of construction, combination and arrangement of parts as will be hereinafter referred 30 to and more particularly pointed out in the specification and claim.

In the accompanying drawings forming a part of this application, Figure 1 is a top 35 plan view of a rail joint chair constructed in accordance with my invention partly in section. Fig. 2 is a similar view showing the same in its open position, parts thereof being illustrated in cross section. Fig. 3 is a detail perspective view of one of the movable fish plates. Fig. 4 is a transverse sectional view taken on the line 4—4, Fig. 1. Fig. 5 is a similar view illustrating the fish 40 plates in their various positions during the removal and replacement of the rail ends; and Fig. 6 is a transverse sectional view 45 taken on the line 6—6, Fig. 2.

In carrying out my invention, I provide a base plate indicated by the numeral 1 and 50 which is formed of heavy sheet metal or cast iron and mounted transversely upon the cross ties. This base plate 1 is provided with the spaced transverse openings 2 and is further provided at the ends of these openings 55 with the longitudinally extending arcuate grooves 3 constituting knuckle seats, the

purpose of which will be hereinafter more fully set forth. Formed integral with the plate and arranged along the outer longitudinal edges of the seats 3, are the retaining ribs 4 which are provided upon their inner faces with recesses 5 closed at their ends by inward projecting shoulders 6. Movable mounted within the seats 3, are the rounded knuckles 7 which are formed upon the outer longitudinal edges of the base flanges 8 of the fish plates, said flanges extending forwardly over the base of the rail, thence in a vertical plane to provide splice plates 9 adapted to embrace the opposed sides of the webs of the rail ends to securely hold the same against lateral movement. Formed upon the inner faces of the knuckles 7, are the spaced ears 10 which are adapted to be disposed within the openings 2, when the rail ends are in their effective positions and are retained in such position by the weight of the rail ends. The splice plates 9 are provided upon their inner faces with inwardly projecting lugs 11 adapted to engage with transverse openings 12 formed in the rail ends, so as to securely retain the rail ends against longitudinal movement. It will be noted that when the fish plates are in their effective positions, as illustrated in Fig. 4, they will be securely held against lateral movement by means of the ribs 4 and the pressure of the rail upon the ears 10, will securely hold the fish plates in their effective positions.

In placing the rail ends in position, the fish plates are opened, as illustrated in Fig. 5, the ears 10 projecting upwardly in an inclined position and the base flanges of the fish plates bearing against the upper edges 90 of the ribs 4. The rail ends are arranged between the fish plates, the bases of the rails engaging with the inner ends of the ears 10, so that when downward pressure is applied to the rail ends, the ears 10 will be pressed downwardly and force the fish plates into engagement with the base flanges and web portions of the rails. It will be apparent 95 that when the fish plates are in their effective positions, the lugs 11 will be disposed within the openings 12 to retain the rail ends against any longitudinal movement. In removing the rail ends from the chair, upward pulling power is applied to the rail ends, so that the fish plates will be forced 100 away from the rail ends to allow the same to be removed from between the fish plates. It

will be noted that the fish plates are mounted for rocking movement, so that the rail ends may be quickly and readily placed in position, or quickly removed from the chair 5 and, at the same time, will be rigidly held against any lateral or longitudinal movement.

It will be apparent from the foregoing description, taken in connection with the accompanying drawings, that I have provided a simple and durable rail joint chair, whereby in the meeting ends of two rails may be effectively connected together, without the use of fastening means and, at the same time, will 10 be securely held against any lateral or longitudinal movement, with respect to the ties. The base plate 1 is provided upon its longitudinal edges, with suitable recesses 13, which are adapted to receive the heads of securing spikes 14 which are driven into the tie to retain the plate against movement.

While I have shown and described the preferred form of my invention, it will be obvious that various changes in the details 25 of construction and in the proportions may be resorted to for successfully carrying my invention into practice, without sacrificing any of the novel features or departing from the scope of the appended claim.

The inner ends of the ears 10 are provided with upwardly projecting rounded bosses 10' which are arranged in spaced relation with the base flanges of the fish plates, so 30 that when the base flanges of the rails are arranged in position, they will be securely clamped between the inclined portions of the fish plates and the aforesaid bosses. It will be apparent that by providing these bosses upon the inner ends of the ears 10, the rail 35 ends can be more readily removed when so desired, than if the ears engaged flat up 40 against the base of the rail. It will be ap-

parent that if the ears 10 engage flat up 45 against the bases of the rails, the base of the rails would be so tightly clamped between the inclined portions of the fish plates and the ears 10, that they could not be readily removed. From this it is thought that the 50 necessity of providing these bosses 10' is apparent.

Having thus described this invention, what I claim is:—

Copies of this patent may be obtained for five cents each, by addressing the "Commissioner of Patents, Washington, D. C."

The combination with the meeting ends 55 of two rails each provided in its web with a plurality of openings, of a base plate provided with longitudinally disposed retaining ribs provided at their ends with inward projecting shoulders, the inner faces of the 60 retaining ribs being formed with knuckle seats, and the bottom of the base plate being furnished with transverse slots, fish plates having knuckles to engage the knuckle seats and provided with ears to project within the 65 slots, the upper face of the inner ends of the ears being provided with rounded bosses to engage with the under side of the base of the rail, splice plates provided with studs to engage with the openings in the rail webs, and a base flange connecting the splice plates and the knuckles, the bosses serving as a means to prevent direct contact between the upper surfaces of the ears and the under face of the rail base, whereby to permit ready lifting of the rails when it is desired to remove the fish plates therefrom, and the shoulders at the ends of the seat serving to prevent any longitudinal movement of the fish plates relative thereto.

In testimony whereof I hereunto affix my signature in the presence of two witnesses:

GEORGE H. EVANS.
